(57) **CLAIM**

The ornamental design for a swift clamp, substantially as shown and described.

DESCRIPTION

FIG. 1 is a perspective view of a swift clamp invention showing our new design.

FIG. 2 is a front view thereof.

FIG. 3 is a right side view thereof.

FIG. 4 is a rear view thereof;

FIG. 5 is a top plan view thereof; and,

FIG. 6 is a bottom plan view thereof.
